[57] ABSTRACT

In a conventional valve assembly having a valve body,

a valve member disposed in the body, and a rotatable valve stem journaled in the body, and a rotatable valve stem journaled in the body and connected at the inner end thereof to the valve member and extending through the body with the outer end thereof having a pair of parallel flat surfaces formed thereon, an apparatus carried by the body for limiting the rotation of the valve stem so that the valve member will stop at either a fully closed or open position. In one form of the apparatus the outer end of the valve stem extends through an aperture formed in a plate which is seated in a groove formed in the valve body. Diametrically opposed shoulders extend radially inward from the aperture wall to engage the flat surfaces of the stem. In another form, the plate is secured to the valve body by means of two pins extending outwardly from the valve body through matching holes formed in the plate. In yet another form, the plate is combined with a means for providing a seal about the stem. Retaining means and cover means for the apparatus are also disclosed.

INDEXING STOP OF VALVE STEM

BACKGROUND OF THE INVENTION

1. Field of the Invention

This invention relates generally to improvements in valves, and more particularly, but not by way of limitation, to apparatus for limiting the rotation of a valve stem.

2. Description of the Prior Art

It is common practice to have an indexing mechanism on any type of rotary valve so that the valve member will stop in either a fully closed or a fully open position when turned by the operator. The most common practice is to provide a lug on a portion of the valve handle which alternately engages one of a pair of spaced lugs formed on the upper end of the neck of the valve body. Such a construction is expensive because of the precise positioning required of the lugs. Further, the lugs are frequently broken off, and the area between the lugs is exposed to foreign material, such as dirt and ice, so that the lugs will frequently not be engaged when the valve member is turned to properly position the valve member in either an open or closed position. Frequently, the introduction of foreign material between the lugs prevents the turning of the valve member at all.

When the lug on the valve handle engages the respective lug formed on the neck of the valve body, continued application of turning force to the valve handle causes the valve stem to be biased away from the lug on the body thereby creating undesirable loading on the stem and the stem sealing means. This situation can lead to premature stem seal failure and accelerated valve wear.

SUMMARY OF THE INVENTION

The present invention contemplates a novel apparatus for limiting the rotation of a valve stem in a valve which includes a valve body having an upstream end face, a downstream end face, and a bore extending therethrough intersecting the end faces. A valve member is disposed within the bore of the valve body intermediate the end faces and is rotatable from a position wherein the bore is open to a position wherein the bore is closed. A valve stem extends through the valve body and is connected at the inner end thereof to the valve member for rotation thereof. A pair of parallel flat surfaces is formed on the outer end of the valve stem. Means for limiting the rotation of the valve stem and the valve member connected thereto between the open and closed positions includes a substantially flat plate rigidly secured to the outer portion of the valve body. An aperture is formed in the flat plate through which the outer end of the valve stem extends. A pair of diametrically opposed shoulders are formed on the inner periphery of the aperture and extend radially inward therefrom a sufficient distance to interfere with the parallel flat surfaces of the valve stem thereby limiting the rotation thereof.

An object of the present invention is to provide an apparatus for limiting the rotation of a valve stem and the valve member connected thereto which is easily fabricated and installed.

Another object of the present invention is to provide an apparatus for limiting the rotation of a valve stem and the valve member connected thereto which effec-

tively prevents the entrance of foreign matter which would foul the precise indexing of the valve stem.

A further object of the present invention is to provide an apparatus for limiting rotation of a valve stem and the valve member connected thereto which performs a sealing function around the valve stem.

A still further object of the present invention is to provide an apparatus for limiting the rotation of a valve stem and the valve member connected thereto which is economical in construction and operation.

Further objects and advantages of the present invention will be evident from the following detailed description when read in conjunction with the accompanying drawings.

BRIEF DESCRIPTION OF THE DRAWINGS

FIG. 1 is a vertical cross-sectional view of a ball valve constructed in accordance with the present invention.

FIG. 2 is a fragmentary cross-sectional view taken along line 2—2 of FIG. 1 and illustrating the valve operating member in the closed position.

FIG. 3 is a fragmentary cross-sectional view similar to FIG. 2 illustrating the valve operating member in the open position.

FIG. 4 is a fragmentary vertical cross-sectional view of another embodiment of ball valve also constructed in accordance with the present invention.

FIG. 5 is a fragmentary cross-sectional view taken along line 5—5 of FIG. 4.

FIG. 6 is a fragmentary plan view taken along line 6—6 of FIG. 4.

FIG. 7 is a fragmentary vertical cross-sectional view of another embodiment of ball valve constructed in accordance with the present invention.

FIG. 8 is a top view of the stop plate illustrated in FIG. 7.

FIG. 9 is a bottom view of the stop plate illustrated in FIG. 7.

DESCRIPTION OF THE PREFERRED EMBODIMENT

Referring to the drawings and to FIGS. 1, 2 and 3 in particular, shown therein and generally designated by the reference character 10 is a ball valve constructed in accordance with the invention. As illustrated therein, the ball valve 10 includes a valve body 12 having a passageway or bore 14 extending therethrough. A transverse passageway or bore 16 of circular cross-section extends through the wall of the valve body 12 intersecting the passageway 14 for purposes that will be described more fully hereinafter. The transverse bore 16 is provided with a counter bore adjacent its intersection with the passageway 14 providing a planar surface 18 in the valve body 12.

A pair of identically constructed seal rings 20 and 22 are disposed in the opposite ends of the ball valve 10 and are in engagement with an upstream end face 24 and a downstream end face 26, respectively, on the valve body 12. The seal ring 20 includes an end face 28 that is in engagement with the inner face 30 of a standard pipe flange 32. The seal ring 22 includes an end face 34 that is in engagement with the inner face 36 of a standard pipe flange 38. The seal rings 20 and 22 are preferably constructed from a relatively rigid material.

A plurality of threaded fasteners 40 extend through the flanges 32 and 38, respectively, and are provided with threaded nuts 42 and 44 that are threaded onto

the threaded fasteners 40 to move the flanges 32 and 38 relatively toward each other.

Located within the passageway 14 in the valve body 12 is a valve member or ball 46 having a flow port 48 extending therethrough. The exterior surface of the valve ball 46 is provided with a rectangular recess or groove 50 sized to receive the rectangular end or tongue 52 of a valve operating member or stem 54.

The valve operating member 54 of substantially circular cross-section extends through the transverse bore 16 and includes a flange 56 formed thereon adjacent the rectangular end 52 thereof. The flange 56 is positioned adjacent the planar surface 18 of the valve body 12, and is separated therefrom by a bearing washer 57 encircling the valve operating member 54, thereby limiting the upward movement of the valve operating member 54 in the passageway 16 of the valve body 12. The bearing washer 57 is preferably constructed of a relatively resilient material such as Teflon. An O-ring seal 58 is located in an annular groove 60 encircling the valve operating member 54. The seal 58 sealingly engages both the valve operating member 54 and the valve body 12 in the transverse bore 16.

The end of the valve operating member 54 extending from the valve body 12 is provided with a pair of parallel flat surfaces 62 and 64 formed thereon and extending from within the valve body 12 to the outer end 66 of the valve operating member 54. A recess is formed in the valve body 12 adjacent the valve operating member 54 forming a planar surface 68 normal to the longitudinal axis of the valve operating member or stem 54 and further forming a pair of parallel walls 70 and 72 substantially normal to the planar surface 68. It should be noted that the flat surfaces 62 and 64 extend into the valve body 12 to a point slightly below the depth of the planar surface 68. A rectangular plate 74 having a substantially circular aperture 76 formed therein, is positioned on the planar surface 68 encircling the valve operating member 54 which extends through the aperture 76 thereof. The plate 74 is prevented from rotating with the valve operating member 54 by the engagement of the parallel edges 78 and 80 thereof, respectively, with the walls 70 and 72 of the recess. A pair of diametrically opposed stops or shoulders 82 and 84 are formed within the aperture 76 of the plate 74 and extend radially inward therefrom. The stops 82 and 84 are sized and shaped such that the flat surfaces 62 and 64 of the valve operating member 54 will be engaged thereby thus limiting the rotation of the valve operating member 54 to 90°.

An interrupted annular groove 86 is formed in the cylindrical segments 88 and 90 of the valve operating member 54 adjacent the upper side 92 of the plate 74. A spring type retaining ring 94 is positioned in the groove 86 and extends radially outward therefrom over the upper side 92 of the rectangular plate 74 in assembled operating position. A dust cap 96, having an aperture 98 formed therein, encircles the upper end portion of the valve operating member 54 and covers the retaining ring 94. The aperture 98 is sized and shaped to conform to the exterior shape of the valve operating member and is adapted to rotate therewith. The dust cap 96 may be conveniently formed of synthetic resin material such as Nylon and may be suitably inscribed with words or symbols indicating the position of the valve ball 46.

It should be noted that the plate 74 may be conveniently formed of a metal stamping. The shape of the plate 74 need not necessarily be rectangular, although this shape simplifies the forming of the mating recess in the valve body 12, but may take on any number of non-circular shapes which would prevent the rotation of the plate 74 with the valve operating member 54.

DESCRIPTION OF THE EMBODIMENT OF FIGS. 4, 5 AND 6

The fragmentary vertical cross-sectional view of FIG. 4 illustrates a modified form of ball valve that is generally designated by the reference character 10a and is also constructed in accordance with the present invention. Many of the components previously described with respect to the ball valve 10 are incorporated in the ball valve 10a and will, therefore, be designated by the same reference characters. As illustrated in FIG. 4, a planar surface 100 is formed on the slightly modified valve body 12a adjacent the valve operating member 54 and normal to the longitudinal axis thereof. A pair of guide pins 102 and 104 are fixedly secured to the valve body 12a in parallel alignment with the longitudinal center line of the valve operating member 54, and extend upwardly a distance from the planar surface 100. An indexing plate 106, having a substantially circular aperture 108 formed therein and having a pair of clear holes 110 and 112 also formed therein, is positioned on the planar surface 100 encircling the valve operating member 54. The clear holes 110 and 112 are sized and positioned in the indexing plate 106 such that the guide pins 102 and 104, respectively, slidably pass therethrough to secure the indexing plate 106 on the planar surface 100 thereby preventing any sliding movement of the indexing plate 106 along the surface 100. A pair of diametrically opposed stops or shoulders 114 and 116 are formed within the aperture 108 of the indexing plate 106 and extend radially inward therefrom. The stops 114 and 116 are sized and shaped such that the flat surfaces 62 and 64 of the valve operating member 54 will be engaged thereby thus limiting the rotation of the valve operating member 54 to 90°.

A dust cover plate 118, having an aperture 120 formed therein, encircles the upper end portion of the valve operating member 54 and is positioned adjacent the upper side 122 of the indexing plate 106. The aperture 120 is sized and shaped to conform to the exterior shape of the valve operating member 54 which extends therethrough and is adapted to rotate therewith. The dust cover plate 118 may be conveniently formed of stamped sheet metal or may be molded of a relatively rigid material such as Nylon or Delrin.

An interrupted annular groove 86 is formed in the cylindrical segments 88 and 90 of the valve operating member 54 adjacent the upper side 124 of the dust cover plate 118. A spring type retaining ring 94 is positioned in the groove 86 and extends radially outward therefrom over the upper side 124 of the dust cover plate 118 thereby retaining the valve operating member 54, the indexing plate 106 and the dust cover plate 118 in assembled operating position.

It should be noted that the indexing plate 106 may be conveniently formed of a metal stamping or other suitable material. It should also be noted that the guide pins 102 and 104 should preferably extend above the planar surface 100 a distance substantially equal to the thickness of the indexing plate 106 thereby providing

a flush surface on the upper side 122 vertical sectional
DESCRIPTION OF THE EMBODIMENT OF FIGS. 7,
8 AND 9

The fragmentary vertical-sectional view of FIG. 7 illustrates another modified form of ball valve that is generally designated by the reference character 10b and is also constructed in accordance with the present invention. As shown therein, the valve body has been modified and is designated by the reference character 12b. A counterbore 126 is formed in the upper end of the slightly modified transverse passageway 16b and forms an upwardly facing annular shoulder 128. A planar surface 130 is formed on the upper portion of the valve body 12b normal to the longitudinal center line of the slightly modified valve operating member 54b. A recess 132 is formed in the upper end of the valve body 12b adjacent the valve operating member 54b and forms a planar surface 134 parallel to the planar surface 130. The recess 132 is preferably in the form of a transverse groove having parallel side walls 136 and 138 which interconnect the planar surfaces 130 and 134.

A combination indexing plate and packing gland follower 140 is disposed in the recess 132 and the counterbore 126. A substantially circular aperture 142 is formed in the plate 140 as is more clearly illustrated in FIGS. 8 and 9. The aperture 142 is sized such that the upper end 66 of the valve operating member 54b extends therethrough. A pair of diametrically opposed projections or shoulders 144 and 146 are sized and positioned in the aperture 142 such that they engage the flat surfaces 62 and 64 of the valve operating member 54b to limit the rotation thereof to 90°. The upper portion 148 of the plate 140 is characterized by a pair of parallel edges 150 and 152 which engage the side walls 136 and 138, respectively, of the recess 132 to prevent the rotation of the plate 140 with the valve operating member 54b. The lower portion of the plate 140 is characterized by an annular gland follower portion 154 which encircles the portion of the valve operating member 54b below the flat surfaces 62 and 64 and extends downwardly between the valve operating member 54b and the counterbore 126. The end face 156 of the gland follower portion 154 engages an annular sealing member or packing gland 158 encircling the valve operating member 54b which is confined by the annular wall 128, the counterbore 126 and the valve operating member 54b. It should be noted that the projections or shoulders 144 and 146 do not extend to the full depth of the plate 140 but are restricted to the upper portion 148 thereof as best shown in FIG. 7.

A bonnet plate 160 is positioned adjacent the upper end of the valve body 12b with the upper end 66 of the valve operating member 54b extending through a circular aperture 162 formed therein. The diameter of the aperture 162 is substantially equal to the diameter of the circular portion of the aperture 142 formed in the plate 140. The bonnet plate 160 is secured to the valve body 12b by a pair of cap screws 164 and 166 passing therethrough and threaded into the valve body 12b. The bonnet plate 160 engages the upper face 168 of the plate 140, and, by tightening the cap screws 164 and 166, the plate 140 is drawn downwardly into the valve body 12b. As the plate 140 is forced downwardly by the bonnet plate 160, the end face 156 of the gland follower portion 154 compresses the confined packing

gland 158 thereby providing a seal between the valve body 12b and the valve operating member 54b.

A dust cover plate 118 as described above is positioned about the upper end portion of the valve operating member 54b adjacent the upper side 170 of the bonnet plate 160. The dust cover plate 118 is secured in position by the previously described retaining ring 94 positioned in the interrupted annular groove 86 formed in the valve operating member 54b, which also rotatably secures the valve operating member 54b to the valve body 12b in assembled operating position.

It should be noted that any loading of the plate 140 resulting from the engagement of the projections 144 and 146 thereof by the flat surfaces 62 and 64 of the valve operating member 54b is transmitted to the valve body 12b by the edges 150 and 152 of the plate 140 to the adjacent side walls 136 and 138, respectively, formed in the valve body 12b. The cap screws 164 and 166 are loaded only in tension and never experience any shear stress due to external force applied to the valve operating member 54b.

From the foregoing detailed description of the various forms of apparatus for limiting the rotation of a valve operating member or stem it can be readily seen that the present invention provides apparatus which is easily fabricated and installed and which effectively prevents the entry of foreign matter which might foul the precise indexing of the valve stem or operating member. It may further be seen that the diametrically opposed stem stops or shoulders eliminate undesirable biasing of the valve operating member or stem within the valve body thereby providing perfect alignment within the stem packing chamber or passageway for dependable, trouble free stem and sealing service.

Changes may be made in the construction and arrangement of parts or elements of the various embodiments as disclosed herein without departing from the spirit and scope of the invention.

What is claimed is:

1. A valve comprising:
a valve body having an upstream end face, a downstream end face, and a bore extending therethrough intersecting the end faces;
a valve member disposed within the bore of said valve body intermediate the end faces and rotatable from a position wherein the bore is open to a position wherein the bore is closed;
a valve stem extending through said valve body and connected at the inner end thereof to said valve member for rotation thereof, and having a pair of parallel flat surfaces formed on the outer end portion thereof;
means for limiting the rotation of said valve stem and said valve member connected thereto between the open and closed positions, including:
an indexing plate rigidly secured to the outer portion of said valve body and having an aperture formed therein through which the outer end portion of said valve stem extends, and
a pair of diametrically opposed shoulders formed on the inner periphery of the aperture and extending radially inward therefrom to engage the parallel flat surfaces of said valve stem thereby limiting the rotation thereof; and
cover means positioned on the outer end portion of said valve stem adjacent said indexing plate for

- preventing the introduction of foreign matter between the valve stem and the indexing plate.
2. The valve as defined in claim 1 wherein said indexing plate is matingly received in a recess formed in the outer portion of said valve body whereby said indexing plate is prevented from rotating about the axis of said valve stem.
3. The valve as defined in claim 1 wherein said indexing plate is secured to said valve body by at least two guide pins, said guide pins being fixedly secured to said indexing valve body and extending through matching guide holes formed in said plate.
4. The valve as defined in claim 2 wherein said indexing plate is secured in said recess by retaining means engaging said valve stem.
5. The valve as defined in claim 4 wherein said cover means is positioned on said valve stem intermediate said indexing plate and said retaining means.
6. The valve as defined in claim 4 wherein said cover means is positioned on said valve stem intermediate said retaining means and the outer end of said valve stem.
7. A valve comprising:
- a valve body having an upstream end face, a downstream end face, a bore extending therethrough intersecting the end faces, and an aperture formed therein intersecting the bore;
  - a valve member disposed within the bore of said body intermediate the end faces and rotatable from a position wherein the bore is open to a position wherein the bore is closed;
  - a valve stem journaled in the aperture of said valve body and connected at the inner end thereof to said valve member for rotation thereof, and having a pair of parallel flat surfaces formed on the outer end portion thereof;
  - means for limiting rotation of said valve stem, including:
  - an indexing plate, having an upper portion and a lower portion, rigidly secured to the outer portion of said valve body and having a substantially circular opening formed therein through which opening the outer end portion of said valve stem extends; and
  - a pair of diametrically opposed projections formed on the inner wall of the opening in said indexing plate and extending radially inward therefrom to engage the flat surfaces of said valve stem and limit the rotation thereof;
  - a cover disposed on the outer end portion of said valve stem adjacent said indexing plate;
  - a counterbore formed in the aperture of said valve body intersecting the outer portion of said valve body;
  - an annular extension formed on the lower portion of the indexing plate coaxial with the opening formed therein, said extension being disposed in said counterbore; and
  - an annular sealing member encircling said valve stem and disposed in said counterbore and sealingly engaged by said annular extension, thereby forming

- a seal between said stem and said valve body.
8. The valve as defined in claim 7 wherein a noncircular recess is formed in the outer portion of said valve body into which recess the upper portion of said indexing plate is matingly received, whereby said indexing plate is prevented from rotating about the axis of said valve stem.
9. The valve as defined in claim 8 characterized further to include:
- means for retaining said annular end face in sealing engagement with said annular sealing member.
  - 10. The valve as defined in claim 9 characterized further to include:
  - an interrupted annular groove formed about the outer end portion of said valve stem; and
  - a retaining ring disposed in said annular groove for axially positioning said valve stem in the aperture of said valve body.
  - 11. The valve as defined in claim 10 wherein said cover is disposed on said valve stem intermediate said retaining ring and said indexing plate.
  - 12. The valve as defined in claim 1 wherein said plate is secured to said valve body by at least two guide pins, said guide pins being fixedly secured to said valve body and extending through matching guide holes formed in said plate, said plate being retained on said guide pins by a retaining ring engaging said valve stem, and wherein said cover is disposed on said valve stem intermediate said retaining ring and said indexing plate.
  - 13. A valve comprising:
    - a valve body having an upstream end face, a downstream end face, and a bore extending therethrough intersecting the end faces;
    - a valve member disposed within the bore of said valve body intermediate the end faces and rotatable from a position wherein the bore is open to a position wherein the bore is closed;
    - a valve stem extending through said valve body and connected at the inner end thereof to said valve member for rotation thereof and having a pair of parallel flat surfaces formed on the outer end portion thereof;
    - a recess formed in the outer portion of said valve body adjacent said valve stem, said recess forming a planar surface substantially normal to said valve stem and a pair of spaced walls intersecting the planar surface and substantially normal thereto;
    - an indexing plate disposed on the planar surface in said recess, said indexing plate having a pair of spaced edges matingly engaging the spaced walls of said recess and having an aperture formed therein through which aperture the outer end portion of said valve stem extends; and
    - a pair of diametrically opposed shoulders formed on the wall of the aperture and extending parallel flat surfaces of said valve stem thereby limiting the rotation thereof.

14. The valve as defined in claim 13 wherein said indexing plate is secured in said recess by retaining means engaging said valve stem.

UNITED STATES PATENT OFFICE
CERTIFICATE OF CORRECTION

Patent No. 3,743,243 Dated July 3, 1973

Inventor(s) Domer Scaramucci

It is certified that error appears in the above-identified patent and that said Letters Patent are hereby corrected as shown below:

- Col. 5 line 1, delete "vertical sectional" and insert
--thereof--
- Col 5 line 5 "vertica-sectiona" should be --vertical cross-
sectional--.
- Col 5 line 25 "th7" should be --the--.
- Col 5 line 58 "aperture 142" should be --aperture 144--
- Col 7 line 12 in Claim 3 before the word "plate" insert
--indexing--
- Col 7 line 11, "indexing" should be cancelled and inserted
after "said" in line 12.

Signed and sealed this 22nd day of January 1974.
